UNITED STATES PATENT OFFICE.

FELIX KAHN, OF CINCINNATI, ASSIGNOR TO F. & L. KAHN & BROTHERS.
OF HAMILTON, OHIO.

DESIGN FOR A STOVE.

SPECIFICATION forming part of Design No. 16,581, dated March 23, 1886.

Application filed February 11, 1886. Serial No. 191,651. Term of patent 7 years.

To all whom it may concern:

Be it known that I, FELIX KAHN, of Cincinnati, Hamilton county, Ohio, have invented a certain new and original Design for Stoves, 5 of which the following is a specification, reference being had to the accompanying print, which exhibits in perspective a stove involving my new design.

My new design has reference to the ornamentation of the door or doors of a stove; and it consists of a swelled door-panel, the swell being margined by imitation hammered work cut by transverse lines of flutings.

In the accompanying print is exhibited a 15 cook-stove having several side doors, the said doors exemplifying my design.

In the print, A indicates an outwardly-

swelled panel upon one of the doors; B, margins of the panel-swell, having surfaces in imitation of hammered work; and C, transverse lines of fluting cutting the margins referred to. 20

I claim—

A design for a stove-door, as herein shown and described, consisting of an outwardly-swelled panel, a panel-margin formed by imitation hammered work, ornamented bands crossing the panels parallel with the margin thereof, and lines of fluting disposed transversely upon the margins. 25

FELIX KAHN.
